UNITED STATES PATENT OFFICE.

PERCY ROBERT DOBSON, OF CALGARY, ALBERTA, CANADA, ASSIGNOR TO BELL EQUIPMENT COMPANY LIMITED, OF CALGARY, CANADA.

DOOR-OPERATING MECHANISM.

Application filed July 21, 1927, Serial No. 207,525, and in Canada June 30, 1927.

My invention is an improvement on door operating mechanisms in which pedal members actuated by a vehicle, open and close the doors through a system of gears and lever arms, and particularly applies to United States application No. 135,209, filed the 13th of September, 1926, and allowed the 3rd of May, 1927, to Percy Robert Dobson.

The objects of my invention are first, to interpose a yieldable resistance between the pedal members and the closing arms. Second, to introduce a mechanism which will allow the actuating pedal members to be quickly depressed during certain operations and to store the energy so transmitted so that the doors may close quietly after the pedal has resumed its vertical position, and third, to introduce a selecting device between the outside pedal and the door closing arms so that the first contact of the leading wheels of an automobile while depressing the exterior pedal will not actuate the apparatus to close the doors but which will actuate the apparatus when depressed a second time by the following wheels of the automobile.

I attain these and other objects by the mechanism illustrated in the accompanying drawings, in which—

Fig. 1 shows a general perspective of the complete apparatus.

Fig. 2 is a vertical longitudinal section through the selecting device A.

Fig. 3 is a plan looking down on the selecting device A.

Fig. 4 is an elevation of the shock absorbing device B.

Fig. 5 is a plan of the quadrant to which the closing arms are attached.

Fig. 6 is a perspective view of an alternative door connection.

Fig. 7 is a longitudinal section through the building showing a locking device.

Fig. 8 is a transverse section showing the locking device.

Similar numerals and letters refer to similar parts throughout the several views:

Referring to the drawings:

1 represents the walls of a building having therein the doors 2 and 3. 4 is the exterior pedal member which normally retains an upright position, the means used for influencing same not being a part of this application. 5 is the interior pedal member which is similar in nature to the exterior pedal 4. 6 and 6^A comprises a divided rod connecting the ex-

terior pedal 4 to the gear 8. 7 is a connecting rod intermediate the interior pedal 5 and the gear 8 already referred to.

The gear 8^A is in mesh with the gear 8 and is carried by on vertical member 9. In line 60 with the member 9 is the member 10 supported in a bracket 13 from the wall 1 of the building. Intermediate the members 9 and 10 is the mechanism B which is hereinafter described in detail. Secured to the member 65 10 is the quadrant 14 to which is pivotally attached the operating arms 15 and 16 which are suitably connected to the doors of the building. It will be evident that rotation of the quadrant 14 by the member 10 will operate the door to a closed or open position.

Mounted upon the connecting rods 6 and 6^A at their junction is the selecting device shown at A and described hereinafter in detail.

The selecting device comprises rod 6^A 75 which is tubular in form and within which the connecting rod 6 engages in slidable relation. The connecting rod 6^A is slotted at 17 for the purpose hereinafter mentioned and also at 18. Carried by the rod 6 is the projecting pin 19 which slides freely in the slot 18 mentioned. Mounted on the rod 6^A is the thrust collar 20 and the thrust collar 21 which carries thereon the bracket 22. These collars are retained by the set screws 23 and 24 or other suitable means. Intermediate the thrust collars 20 and 21 and surrounding the rod 6^A is the tubular sleeve 25 which is partly cut away at 26 as shown on drawing. On the sleeve 25 is formed the arm 27 with which is engaged the plunger 28 which passes through a hole 29 in the bracket 22. The plunger is influenced by the compression spring 30 with the object of holding the sleeve 25 left or right of its dead centre when it is so turned.

A thrust collar 31 is mounted upon the rod 6, and retained by the set screw 32. Intermediate the collar 31 and the end of the rod 6^A is the compression spring 33. An anchor bolt 34 is engaged in the slot 17 and intermediate same and the connecting eye 35 formed on the end of rod 6 is the tension spring 36. The springs 33 and 36 are inserted to lessen the shocks due to abrupt operation and otherwise to make the device operate smoothly.

Formed on the underside of sleeve 25 is a projecting catch 37 and in relation thereto is the spring influenced plunger 38. The plunger 38 is mounted in a socket 39 and is 110

influenced by the compression spring 40. The plunger 38 engages the catch 37 during the operation of closing the doors when leaving the building after wheel depresses pedal 4.

6 The shock absorbing device hitherto mentioned as B comprises the hollow shaft members 9 and 10 already mentioned. Passing into same and holding them in alignment is the shaft 41 upon which is rigidly fixed the collar 42. Wound around the shaft 41 is the double coil spring 43 which reverses its direction where engaged with the collar 42. The upper and lower ends of the spring 43 are fastened to the tubular members 10 and 9 respectively. The wall of member 9 is partly cut away at 44 and there passes through the opening the pin 45 which is fastened to the inner shaft 41. The wall of member 10 is similarly cut away at 46 and allows the pin 47 which is mounted on the shaft 41 to protrude. These pins 45 and 47 allow the upper or lower portion of the spring 43 to be wound up without simultaneous motion of the members 9 and 10.

25 In the quadrant 14 already mentioned are formed the hole 48 to which one of the door operating arms is pivotally engaged. A slotted hole 49 in the quadrant gives an adjustable point of support for the second door operating arm. It is thus possible to have one door leaf close slightly in advance of the other and some such provision is necessary where the doors are rebated on their meeting edges.

35 In operation commencing with the car outside the building, the doors being closed, and the sleeve 25 in the position shown in Fig. 3. The car approaching depresses the pedal 4 towards the building and through the thrust 40 of connecting rods 6 and 6^A actuates the gear 8 and thereby the gear 8^A and the vertical shaft 9. The spring 43 acting as a flexible connection between the shafts 9 and 10 the quadrant 14 is rotated without shock and the doors are opened. In the thrust of the connecting rod 6 the pin 19 is driven towards the larger end of the opening 26 and due to the curvature of same the sleeve is partly rotated in a counter clockwise direction beyond its vertical dead centre where it is retained by the influence of spring 30. When the car proceeds into the building the rear wheels again depress pedal 4, but as 6^A is at the limit of its travel there is no further effect on the gear 8. The front wheels of the car then depress pedal 5 which through rod 7 reverses the motion of gear 8 thereby closing the door. In use the front wheel of the car overruns pedal 5.

60 In withdrawing from the building, the front wheel depresses pedal 5 towards the doorway opening the doors and proceeding through same the rear wheels of the car first encounter the exterior pedal 4. As the pin 19 is now clear of the small notch in the sleeve

25 the pull on acting rod 6 is ineffective to operate gear 8, the pin travelling along the narrow portion of the opening 26. This motion rotates the sleeve 25 in a clockwise direction so that when the rear wheel has passed over 70 pedal 4 and same returns to its vertical position, the pin 19 travels forward by means of spring 36 and engages in the notch in opening 26 already referred to. When the front 75 wheels depress pedal 4 the rods 6 and 6^A act as a solid unit and the whole selecting device A is pulled forward towards the door. The catch 37 is now in a position to engage the spring plunger 38 thereby holding the spring 43 of the device B in a condition to close the 80 doors 2 and 3. That is a car leaving the building need not hold the pedal 4 depressed until the doors are actually closed since the engagement of catch 37 with plunger 38 is effective towards the same end.

85 What I claim is:

1. The combination with door operating mechanisms employing exterior and interior pivotal pedal members actuated by vehicle wheels, a divided shaft intermediate the exterior pedal member and the remaining mechanism, a rotatable sleeve engaging the divided shaft at the junction thereof, means of rotating the sleeve through the intersection of the portions of the divided shaft, the whole being so adapted that the position of the sleeve will unite the divided shaft, co-ordinating the motion of the exterior pedal with the door operating mechanism or alternately disunite the divided shaft making the motion of the exterior pedal ineffective.

2. The combination with door operating mechanism employing exterior and interior pivotal pedal members actuated by vehicle wheels, two shafts with telescopic engagement intermediate the exterior pedal and the remaining mechanism, a pin mounted on the interior shaft and passing through a slot in the wall of the exterior shaft, a rotatable sleeve surrounding the shafts at their junction the said sleeve being cut away to engage the said pin on the interior shaft, the rotatable sleeve being so adapted that its engagement with the said pin will unite the shafts to co-ordinate the motion of the exterior 105 pedal and the remaining mechanism, or alternately in another position make the co-ordination ineffective.

3. The combination with door operating mechanism employing exterior and interior pivotal pedal members actuated by vehicle wheels, two shafts with telescopic engagement intermediate the exterior pedal and the remaining mechanism, a pin mounted on the interior shaft and passing through a slot in the wall of the exterior shaft, a rotatable sleeve surrounding the shafts at their junction the said sleeve being cut away to engage the said pin on the interior shaft, the rotatable sleeve being so adapted that its en- 110

gagement with the said pin will unite the shafts to co-ordinate the motion of the exterior pedal and the remaining mechanism, or alternately in another position make the co-ordination ineffective; spring means in relation to the junction of the shafts to reduce the shock of engagement, and spring means to hold the rotatable sleeve in its alternate positions.

- 10 4. The combination with door operating mechanism employing exterior and interior pivotal pedal members actuated by vehicle wheels, two shafts with telescopic engagement intermediate the exterior pedal and the
- 15 remaining mechanism, a pin mounted on the interior shaft and passing through a slot in the wall of the exterior shaft, a rotatable sleeve surrounding the shafts at their junction the said sleeve being cut away to engage
- 20 the said pin on the interior shaft, the rotatable sleeve being so adapted that its engagement with the said pin will unite the shafts to co-ordinate the motion of the exterior pedal and the remaining mechanism, or al-

ternately in another position make the co-ordination ineffective; a lug on the aforesaid rotatable sleeve, a spring influenced plunger in relation to the said lug and adapted to engage same for the purpose specified.

- 25 5. The combination with door operating mechanism employing exterior and interior pivotal pedal members actuated by vehicle wheels, a tubular vertical shaft in relation to the pedal members, means intermediate the 30 pedals and the vertical shaft actuating the shaft when either pedal is depressed, an upper tubular shaft carrying door operating arms, a rod intermediate the two shafts and engaged in the bores thereof and having limited rotational motion relative to the shafts, a spring secured to the rod about its centre and at its free ends to the shafts respectively forming a yieldable connection between the two shafts, means of holding the first named 40 shaft after actuation, comprising a lug on a rotatable sleeve engaging a spring influenced plunger in relation thereto.

PERCY ROBERT DOBSON.
